UNITED STATES PATENT OFFICE.

JOHN WEBER, OF TOLEDO, OHIO, ASSIGNOR TO THE TOLEDO METAL WHEEL CO., OF TOLEDO, OHIO, A CORPORATION OF OHIO.

RUNNING-GEAR.

SPECIFICATION forming part of Letters Patent No. 726,598, dated April 28, 1903.

Application filed November 6, 1902. Serial No. 130,269. (No model.)

To all whom it may concern:

Be it known that I, JOHN WEBER, a citizen of the United States, residing at Toledo, in the county of Lucas and State of Ohio, have 5 invented certain new and useful Improvements in Running-Gear, of which the following is a specification, reference being had therein to the accompanying drawings.

The invention has reference generally to 10 an improved type of running-gear especially designed in use for a toy or child's wagon; and it consists in the novel construction of the portion of the gear attached to the front of the wagon.

15 The invention further consists in the means employed for securing the tongue to the gear and in various other details of construction, as will be more fully hereinafter set forth.

In the drawings illustrating my invention, 20 Figure 1 is a perspective view of that part of the gearing attached to the front axle of the wagon, the parts of the fifth-wheel coupling being shown detached. Fig. 2 is a vertical central section through the coupling, the parts 25 being assembled, and through the connecting means for the tongue.

The reference-letter A represents the front axle of the wagon, upon which is supported the front bolster B, formed of a bent metallic 30 bar. The ends of the bolster are connected to the axle in the manner indicated, while angle-braces C connect the central portion of the axle to the bolster.

D represents one of the members of the fifth-wheel coupling in the form of a slotted disk E, having downwardly and laterally projecting ears F. This member is arranged upon 35 the central portion of the bolster and is connected thereto by bolts G, which extend through the ears F and the transverse portions H of the angle-braces, as plainly shown in Fig. 1. The slot I, formed within this coupling member, has its open end extending rearwardly of the bolster, as shown.

40 J designates a support for the wagon-body, preferably in the form of three upwardly-extending brace-bars a, the upper ends being attached to the body in any suitable manner and the lower ends being overlapped, as shown 45 in Fig. 2.

K designates the complementary or coöp-

erating coupling member, which is carried by and clamped to the body-support in the manner hereinafter described.

As illustrated, the coöperating member consists of two circular separated plates K' and L, spaced from each other by a spacing member M in the form of a circular plate or collar, and an annular flange O, depending from the upper and larger plate K'. A bolt P, carrying preferably integral with it the collar M referred to, extends through the separated plates and also through the overlapping ends of the members constituting the wagon-body support and serves to clamp the parts rigidly 55 together. The coupling members are assembled by inserting the collar or spacing member M in the slot I and then turning the coöperating member through one-half of a revolution, so that the depending flange O will 60 encircle the slotted member E of the coupling and prevent disengagement of the parts. As thus assembled, the separated plates engage upon opposite sides of the slotted disks, and the parts together form an equivalent of the 65 usual king-bolt or circle-plate ordinarily used in a gear of this character.

Attached to the bolster B is a frame or bracket Q, formed of a flat bar of metal bent at or near its middle to form a U-shaped section R and outwardly-projecting arms S. At their ends the arms are twisted so that the extreme end portions will lie in a plane parallel with the bolster and are connected to the under side of the latter by the bolts G, 80 which secure the coupling member and angle-braces to the bolster.

T designates the wagon-tongue, attached to the U-shaped section R of the bracket by ears U. The ears embrace the bracket, as 85 shown, and are connected thereto by a transverse bolt V, forming the pivotal connection between the tongue and the running-gear.

It will be observed from the construction and arrangement of the parts that the front 90 axle with the gear thereon may be readily and quickly detached from the wagon-body when desired. In use, however, the axle will be held securely against detachment through the agency of the flange and collar described. 95

What I claim as my invention is—

1. In a running-gear, the combination with

- a bolster, of a coupling member thereon provided with an open slot extending from its center to its outer edge and a coöperating coupling member comprising two spaced 5 plates engaging on opposite sides of said member, and a dependent flange encircling said slotted member.
2. In a running-gear, the combination with a bolster, of a coupling member thereon provided with an open slot extending from its center to its outer edge, and a coöperating coupling member comprising two separated plates engaging on opposite sides of the slotted member, a spacing member interposed 10 between the plates and engaging the slot, and an annular flange depending from the upper plate and encircling said slotted member.
3. In a running-gear, the combination with the bolster, of a coupling member thereon provided with an open slot extending from its center to its outer edge, and a coöperating coupling member comprising two separated plates engaging on opposite sides of the slotted member, a spacing member interposed 15 between the plates and engaging the slot, and a segmental flange depending from the upper plate and arranged to encircle the edge of the slotted coupling member opposite the slot when the parts are in their coupled position.
4. In a running-gear for wagons, the combination with a bolster, of a slotted coupling member thereon, a wagon-body support, consisting of a plurality of upwardly-extending 20 brace members overlapping at their lower ends, a bolt connecting the overlapping portions of the braces, and a coöperating coupling member carried and clamped to the wagon-body support by the bolt.
5. In a running-gear for wagons, the combination with a bolster, a coupling member comprising a disk provided on its face with a slot open at one end and with a pair of downwardly and outwardly extending ears, 25 means for securing said ears to the bolster, and a coöperating coupling member comprising two separated plates engaging on opposite sides of the slotted disk, and a segmental flange depending from the upper plate and 30 partially encircling said slotted member.
6. In a running-gear for wagons, a bolster provided with downwardly-extending end portions, an axle passing through said end portions, a slotted coupling member on the 35 top of said bolster, braces between the axle and the bolster having their lower ends apertured to receive the axle and their upper ends bent to underlie the bolster, bolts for clamp-
- ing the slotted member, the bolster and upper ends of the braces together, and a coöperating coupling member adapted to engage the slotted coupling member.
7. In a running-gear for wagons, a bolster provided with downwardly-extending end portions, an axle passing through said end 60 portions, a slotted coupling member on the top of said bolster, braces secured to the axle and extending upwardly to the bolster, a yoke-shaped member having its ends interposed between the upper ends of the braces and the bolster, means for clamping the slotted coupling member, the bolster, the ends of the yoke-shaped member and the upper ends of the braces together, and a coöperating coupling member adapted to engage the slotted coupling member.
8. In a running-gear for wagons, a bolster provided with downwardly-extending end portions, an axle passing through said end 65 portions, a slotted coupling member on the top of said bolster, braces between the axle and the bolster having their lower ends apertured to receive the axle and their upper ends bent to underlie the bolster, a yoke-shaped member having its ends twisted to lie flat between the bolster and the upper ends of the braces, bolts for clamping the slotted coupling member, the bolster, the twisted ends of the yoke-shaped member and the upper ends of the braces together, and a coöperating coupling member adapted to engage with the slotted member.
9. In a running-gear for wagons, a bolster provided with downwardly-extending end portions, an axle passing through said end 70 portions, a disk provided on its outer face with a slot open at one end and with a pair of downwardly and outwardly extending ears, braces between the axle and the bolster having their lower ends apertured to receive the axle and their upper ends bent to underlie the bolster, a yoke-shaped member having its ends twisted to lie flat between the bolster and the upper ends of the braces, bolts for clamping the ears of the slotted disk, the bolster, the ends of the yoke-shaped member and the ends of the braces together, and a coöperating coupling member adapted to engage with the slotted member.
10. In testimony whereof I affix my signature in presence of two witnesses.

JOHN WEBER.
